UNITED STATES PATENT OFFICE.

WILLIAM WARNER MURCH, OF NEW YORK, N. Y., ASSIGNOR OF ONE-HALF
TO SAMUEL SPRAGUE HOLDEN, OF NEW YORK, N. Y.

JAW-WRENCH.

SPECIFICATION forming part of Letters Patent No. 759,824, dated May 10, 1904.

Application filed August 7, 1903. Serial No. 168,628. (No model.)

To all whom it may concern:

Be it known that I, WILLIAM WARNER MURCH, a citizen of the United States, and a resident of the city of New York, borough of Brooklyn, in the county of Kings and State of New York, have invented a new and Improved Jaw-Wrench, of which the following is a full, clear, and exact description.

The object of the invention is to provide a new and improved jaw-wrench arranged to permit the operator to readily open or close the jaws to snugly fit the article to be turned and to allow convenient turning of the jaw-carrier and the jaws thereon in either a forward or backward direction.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional face view of the improvement. Fig. 2 is a sectional plan view of the same. Fig. 3 is a face view of the improvement, and Fig. 4 is a perspective view of one of the jaws.

The head A of the wrench is provided with a suitable handle B, adapted to be taken hold of by the operator for conveniently manipulating the wrench, as hereinafter more fully explained, and in the said head is formed a bearing for a revoluble jaw-carrier C, formed of top and bottom disks C' and C'', and a ratchet-wheel C³, interposed between the said disks and fastened to the same by rivets C⁴, as plainly shown in the drawings. The disks C' and C'' are formed with diametrically-disposed slots C⁵ and C⁶, and in the slot C⁵ are mounted to slide toward and from each other jaws D and D', between which the article to be turned is engaged when using the wrench, as hereinafter more fully described. The jaws D and D' are provided with shanks D² and D³, engaging curved slots E' and E² in a disk E, mounted to turn in the ratchet-wheel C³ of the jaw-carrier C, and on the said disk

E is secured a handle F, under the control of 50 the operator, for turning the said disk E to move the jaws D and D' toward and from each other in the slot C⁵ of the jaw-carrier to engage or disengage the article to be turned.

On the ends of the shanks D² and D³ are 55 pivoted lugs D⁴ and D⁵, having their bottoms beveled and engaging the beveled face of a jam-nut F², screwing on the threaded shank F' of the handle F to lock the lugs D⁴ and D⁵, and consequently the jaws D and D', in position after the jaws are adjusted toward or from each other on turning the handle F, as previously mentioned. The jam-nut F² extends through a suitable guideway A', attached to the head A or to the ring C² on the 65 face opposite the one on which the jaws D and D' project, (see Fig. 2,) and by this arrangement dust and other impurities are prevented from passing to the working parts of the wrench, as above described. 70

Now from the foregoing it will be seen that when the jam-nut F² is unscrewed on the shank F' and the operator turns the handle F then the disk E is turned to cause the jaws D and D' to move toward or from each other, according to the direction in which the handle F is turned, and when the jaws D and D' have been adjusted the desired distance apart then the operator screws the jam-nut F² up to engage the same with the lugs D⁴ and D⁵ to securely 80 lock the lugs, and consequently the jaws, in position to hold the jaws against accidental displacement. Now in order to impart a ratchet movement to the jaw-carrier C and the jaws D and D', as well as to the disk E, handle F, and nut F², the following device is provided: The ratchet-wheel C³ of the jaw-carrier C has each side of each tooth formed of two bevels extending inwardly, as plainly indicated in Fig. 1, and the teeth of the ratchet-wheel are 85 adapted to be engaged by a pawl G, mounted to slide lengthwise in the bore B' of the handle B and adapted to be given a half-turn in the said handle by the operator for reversing the pawl to turn the ratchet-wheel, and consequently the jaw-carrier and jaws, in a reverse direction whenever it is desired to do so. The pawl G is provided with a reduced stem G', ter- 90 95

minating at its outer end in a knob G^2 , the shank G^3 of which is polygonal in cross-section to engage a correspondingly-shaped recess or socket B^2 , formed in the outer end of the handle B at the bore B' to hold the pawl G against turning as long as the shank G^3 engages the said socket B^2 . Now when the operator pulls the knob G^2 outward to disengage the shank G^3 from the socket B^2 then the operator can give a half-turn to the pawl G to reverse the same relative to the teeth of the ratchet-wheel C^3 . The pawl G is held normally in an innermost position—that is, in engagement with a tooth of the ratchet-wheel—by the action of a spring H , coiled on the stem G' within the bore B' , one end of the spring resting on a collar I , fastened to the stem G' , the other end of the said spring abutting against a collar I' , having a transverse pin I^2 , fitting a longitudinal slot G^4 , formed in the stem G' . The collar I' rests against a bearing J , in which the stem G' is fitted to slide, the bearing being fastened in the bore B' by set-screws J' , screwing in the handle B , as plainly indicated in Fig. 1. Normally the spring H holds the pawl G in an innermost position for the pawl to engage the teeth of the ratchet-wheel; but the said spring allows the pawl to slide outward when its beveled back glides over the outer bevel of an adjacent tooth on the return stroke of the handle B ; but this outward movement of the pawl G is not sufficient to disengage the shank G^3 from the socket B^2 , and consequently the pawl G is not liable to turn accidentally while using the wrench. When, however, the operator pulls the knob G^2 outward to disengage the shank G^3 from the socket B^2 for reversing the position of the pawl G by giving a half-turn to the pawl, as previously described, then the spring H is pressed, and as soon as the operator releases the knob G^2 the spring returns the pawl to its innermost reversed position. When the wrench is used and the nut or like article to be turned is engaged between the jaws D and D' , as previously described, then the operator on swinging the handle B in the direction of the arrow a' causes the pawl G to engage the innermost bevel of the first tooth on the ratchet-wheel C^3 , thereby turning the ratchet-wheel, and consequently the jaw-carrier and with it the jaws D and D' , to turn the nut or like article. When the operator swings the handle B in the inverse direction of the arrow a' , then the beveled back of the pawl G glides over the outer bevel of the next rearward tooth, and consequently the jaw-carrier and connected parts remain at a standstill during the return stroke of the handle B , and on the next forward stroke of the handle the jaw-carrier, jaws, and nut engaged are again turned, as above described. When the nut of a wagon-axle, for instance, has been unscrewed, it can be readily held between the jaws D and D' , and when it is desired to again screw the nut upon the axle then the operator

first pulls the knob G^2 outward, then gives a half-turn to the pawl, after which the pressure on the knob G^2 is released, so that the pawl G returns to its former position, but reversed, and consequently when the operator imparts a swinging motion to the handle B in the direction of the arrow a' then the pawl glides over the teeth of the ratchet-wheel C^3 , and the jaw-carrier, jaws, and nut remain stationary, and on swinging the handle B in the inverse direction of the arrow a' the said jaw-carrier, jaws, and nut are turned to screw the nut upon the axle.

When it is desired to remove the pawl G for repairs or other purposes, it is only necessary to loosen the set-screws J' and to pull on the knob G^2 to draw the entire pawl, spring H , collars I and I' , and bearing J out of the handle. In a like manner the pawl and connected parts can be reinserted in the handle and retained in position therein by fastening the bearing J in the handle on screwing up the screws J' .

From the foregoing it will be seen that a forward or backward ratchet motion can be given to the jaw-carrier and its jaws, and the jaws can be readily adjusted toward or from each other to snugly fit the article to be turned, and the jaws can be securely locked in position after they are adjusted by screwing up the jam-nut F^2 , as previously explained.

Having thus described my invention, I claim as new and desire to secure by Letters Patent—

1. A wrench having a handled head, a jaw-carrier mounted to turn in the said head, a disk inside said carrier mounted to turn therein and provided with curved slots, jaws fitted to slide toward and from each other in the said jaw-carrier and having shanks engaging the said slots, means connected with said disk and extending to the outside of the head for turning the said disk, and means for locking the said jaws in position after they are adjusted, as set forth. 100

2. A wrench having a jaw-carrier mounted to turn, a disk mounted to turn in the carrier and provided with curved slots, jaws fitted to slide in the jaw-carrier and having shanks engaging the said slots, beveled lugs on the said shanks, and a jam-nut for engaging the said lugs, as set forth. 115

3. A wrench having a jaw-carrier mounted to turn, a disk mounted to turn in the carrier and provided with curved slots, jaws fitted to slide in the jaw-carrier and having shanks engaging the said slots, beveled lugs on the said shanks, a jam-nut for engaging the said lugs, and a threaded handle for turning the said disk and on which screws the said jam-nut, as set forth. 120

4. A wrench having a handled head, a jaw-carrier mounted to turn in said head, a rotatable disk within said carrier, said disk having oppositely-disposed eccentric slots, jaws 130

fitted to slide to and from each other in said carrier and having shanks engaged by said slots, and a bolt connected with said disk at the center thereof for rotating the disk, said 5 bolt extending outwardly between the jaws of the wrench and projecting at one side of the handled head.

5. A wrench having a jaw-carrier mounted to turn, a disk mounted to turn in the carrier 10 and provided with curved slots, jaws fitted to slide in the jaw-carrier and having shanks engaging said slots, beveled lugs on said shanks, a bolt engaging said disk to rotate the same, said bolt having a threaded portion, and a bevelled nut carried upon the threaded portion of 15 said bolt for engaging said beveled lugs to lock said jaws.

6. A wrench having a handled head, a jaw-carrier mounted to turn in said head, said jaw-carrier comprising parallel disks held on opposite sides of said head and having parallel 20 diametrical slots, a ratchet-ring between said

disks and rigidly connected therewith, a central disk fitting within said ratchet-ring and provided with eccentric slots, jaws fitted to 25 slide in the slots formed in said first-named disks and having shanks engaged by the slots in the central disk, a bolt engaging said central disk to rotate the same and extending outwardly beyond the head of the wrench, at the 30 rear side thereof, said shanks of the jaws carrying beveled lugs also extending outwardly beyond the rear side of said head, a beveled nut carried upon said bolt for engaging said lugs to lock the jaws, and, a reversible spring-controlled pawl for engaging said ratchet-ring.

In testimony whereof I have signed my name to this specification in the presence of two subscribing witnesses.
